UNITED STATES PATENT OFFICE

147,676

DESIGN FOR A TABLE LAMP

Hector K. MacQuarrie, San Francisco, Calif.

Application May 31, 1946, Serial No. 130,309

Term of patent 14 years

(Cl. D48—20)

To all whom it may concern:

Be it known that I, Hector K. MacQuarrie, a citizen of the United States, residing in the city and county of San Francisco, State of California, have invented a new, original, and ornamental Design for Table Lamp, of which the following is a specification, reference being had to the accompanying drawings, forming a part thereof.

Fig. 1 is a perspective view of a table lamp of my invention;

Fig. 2 is a side view of said table lamp; and,

Fig. 3 is a rear view of said table lamp.

I claim:

The ornamental design for a table lamp, as shown.

HECTOR K. MACQUARRIE.
